UNITED STATES PATENT OFFICE.

JACOB VON GUNTEN, OF MASSILLON, OHIO, ASSIGNOR TO THE OHIO DRILLING COMPANY, OF MASSILLON, OHIO, A CORPORATION OF OHIO.

WELL-CASING SHOE.

Application filed May 31, 1923. Serial No. 642,409.

The invention relates to shoes for sinking well casings and the objects of the improvement are to provide a shoe having an external annular shoulder to support the gravel which is usually placed around the well casing and carried down therewith, as it is lowered into the ground; to provide a shoe of this character which is substantially cylindrical externally and conical internally; and to provide a steam or water chamber within the shoe communicating at intervals with ports extended through the lower narrow edge of the shoe, the steam or water supply pipe being connected with the chamber in the shoe and extended upward upon the outside of the casing within the hole cut by the shoe.

10 The above and other objects are attained by constructing the invention as illustrated in the accompanying drawing, in which—

15 Figure 1 is a longitudinal sectional view through a shoe embodying the invention, showing the same attached to a casing;

Fig. 2, a bottom plan view of the shoe; and

Fig. 3, a sectional view through a shoe embodying the invention, in which the steam or water is eliminated.

20 Similar numerals of reference indicate corresponding parts throughout the several figures of the drawing.

The well casing which is indicated at 1, may be of any usual construction, and is preferably perforated as shown. The shoe 25 2 as shown in Figs. 1 and 2, is provided with the upward extending annular flange 3 into which the lower end of the casing is inserted, and attached as by rivets 4 or any other manner, an internal shoulder 5 upon 30 the shoe preferably engaging the lower edge of the casing.

The shoe proper is substantially cylindrical externally as shown at 6, and is conical internally as shown at 7, tapering downward from the internal shoulder 5 to the narrow lower edge 8.

An external, horizontal, annular shoulder 9 of a substantial width is provided upon the shoe for supporting the gravel indicated at 50 10, which is usually placed around the casing within the hole 11 formed by the sinking of the shoe in the ground.

This construction is advantageous in that it permits the placing of a tubular wall of 55 gravel around the casing in order that the

same may be carried down therewith by the weight of the gravel added to the weight of the case, as the casing is forced into the ground. The shoulder keeps the gravel from passing the shoe.

An annular water or steam chamber 12 is formed in the shoe and a plurality of ports 13 are cast in the shoe or drilled upward from the lower narrow cutting edge 8 into said chamber, so that when water or steam under pressure is supplied to the chamber, a discharge of the same through these ports serves to soften and loosen the earth and facilitates the cutting action of the shoe.

Especially in going through clay formations, this hydraulic action is necessary and desirable as it breaks down the clay walls which would otherwise prevent the downward movement of the shoe and casing. These walls are commonly formed between the outside of the shoe and the outside of the baler ordinarily used to remove the earth and gravel at the bottom of the hole. By forcing water or steam under pressure through the shoe in this manner, the clay walls thus formed are continually broken down and softened, permitting the baler to pick them up and carry them to the surface. Also water forced through this shoe will supply water for the baler in going through dry strata.

A water or steam supply pipe 14 is connected with the chamber 12 at the shoulder 9 and extends upward along the outside of the casing, within the hole 11 cut by the shoe, to a source of water or steam supply and pressure at the surface of the ground.

By this arrangement, it will be seen that the softening and loosening of the earth under the cutting edges of the shoe can proceed at the same time that the drilling operation is in progress through the casing, so that the drilling operation is not interrupted by inserting steam or water pipes downward through the casing to soften and loosen the earth at the bottom of the hole.

In Fig. 3 is illustrated an embodiment of the invention in which the water chamber is eliminated; the shoe 2a having the flange 3a for attachment to the casing 1 and having the substantially cylindrical exterior 6a and the concaved interior 7a terminating in the narrow cutting edge 8a, a shoulder 9a being formed upon the upper portion of the shoe to hold the gravel as above described.

I claim:—

1. A shoe for well casings provided with a water chamber, ports communicating with the water chamber and extended through the lower edge of the shoe and a pipe connected to the water chamber and extended upward alongside of the casing.
2. A shoe for well casings having a narrow lower edge, a substantially horizontal shoul-

der adapted to support gravel placed around the well casing, a water chamber within the shoe, ports communicating with the water chamber and extended downward through the lower edge of the shoe, and a pipe communicating with the water chamber through said shoulder and extended upward along the outside of the casing.

JACOB VON GUNTEN.
